UNITED STATES PATENT OFFICE.

JOHN J. CLAUSE, OF CHICAGO, ILLINOIS.

DELIVERY APPARATUS.

SPECIFICATION forming part of Letters Patent No. 248,024, dated October 11, 1881.

Application filed July 2, 1881. (No model.)

To all whom it may concern:

Be it known that I, JOHN J. CLAUSE, of Chicago, Cook county, State of Illinois, have invented certain new and useful Improvements 5 in Sheet-Delivery Apparatus for Printing-Presses, of which the following is a specification.

My invention relates to improvements in the mechanism of that class of newspaper-folding 10 machines wherein two contiguous sheets are collected together, one on top of the other, as they come from the press.

In the accompanying drawings, which form a part of this specification, and in which similar letters of reference indicate like parts, Figure 1 is a diagram or cross-sectional view of a device embodying my invention, showing the parts in position to seize the sheet and carry it around the cylinder. Fig. 2 is a similar view, 20 showing the parts in position to release and discharge the sheet from the cylinder. Fig. 3 is a side view. Fig. 4 is a detail sectional view of the cams and their supports.

In said drawings, A represents a portion of 25 the frame of the folding-machine; B, the gripping-cylinder, provided with grippers b, of the usual form; c c' c'', the conveying-tapes, which lead the sheets of paper from the printing-press; c³ c³, the tape-pulleys, and c⁴ the guide 30 or guard extending part way around the gripping-cylinder. Said grippers are actuated at proper intervals by a halved cam, D D', which has contact with a roller, b', upon the end of a crank-arm, b², upon the end of the shaft b³, 35 which has bearings in the arms of the cylinder B, and to which the series of grippers are rigidly secured. Both parts of the cam are similarly shaped, and neither revolves with the shaft B', which they encircle, and whereby the cylinder 40 B is supported and rotated; but they differ in that one, D, is oscillated and the other, D', is stationary. Both are supported upon a sleeve-extension, d, of the hanger D², within which the shaft B' revolves, and which is supported 45 from a transverse portion of the frame A upon the opposite side of the cylinder from that given in Fig. 3, and as shown in Fig. 4.

The oscillating cam, which, of course, is loose upon said sleeve, is actuated by a rod, E, eccentrically joined to a gear, E', meshing with the gear B² upon the shaft B'. The stationary

part is threaded or otherwise rigidly held by the sleeve. The connection of the rod E with the gear E' is through a yoke, e, standing out from the side of the gear to avoid interference 55 with the gear-journal. The gears E' and B² are relatively so proportioned that the former revolves once while the latter revolves twice.

With this construction of the sheets which are fed along by the tapes through the rollers 60 c³ each alternate one is caused to be seized by the grippers and carried around the cylinder B during one revolution thereof. The grippers are caused to open to receive the sheet when they reach the position shown in Fig. 1 by the contact between the roller b' and the cams, and to close upon the sheet as soon as the roller has passed the eccentric surface of the cam, as shown in dotted lines in the same figure. During this operation the two halves of the cam remain coincident, or substantially so, so that the gripper remains open during a short time only. At the next revolution of the cylinder, however, while the gripper is opened at the same point and the sheet released, the oscillating 65 cam will have moved to the position shown in Fig. 2, thereby doubling the length of the eccentric surface which affects the gripper, the roller b' being compelled to pass first over the stationary cam and then over the moving one. 70 This prevents the closing of the gripper at the second revolution until after it has passed the point at which the sheets are seized, so that every second sheet travels along the tapes without being taken up by the cylinder. 75

It has been customary heretofore to employ switches with this class of cylinders to turn off the sheet therefrom at the proper point in its revolution; but I find that with the cylinder placed above the carrying-tapes, as shown by 80 me, the switches may be safely dispensed with. This may be owing to the adhesion resulting from bringing the sheets of paper together, or the centrifugal action, or the gravity which pulls the front end of the sheet down when it is released by 85 the gripper, or all combined. By thus dispensing with an unnecessary feature the mechanism is very much simplified. A series of small rollers, F, are located just above the point where the sheets are released by the gripper, the action whereof is to press the sheet closely against the cylinder and insure its continued move- 90 95 100

moment after its release from the griper until it comes in contact with the succeeding sheet.

I claim—

1. The combination, with the gripers mounted upon a shaft having a crank and roller for communicating motion, of the halved cam, whereof one part is stationary and the other part is oscillated to lengthen the action of the cam at alternate revolutions of the cylinder, and mechanism, substantially such as described, for oscillating said movable part, substantially as set forth.

2. The described means for imposing one sheet upon the other, consisting of the delivery-tapes, the cylinder located above the tapes and provided with gripers timed to seize the

alternate sheets and to release them at the end of a revolution, substantially as set forth, whereby the necessity of a switch to turn off the sheet is obviated.

3. The combination, with the gripers mounted upon a shaft having a crank and roller for communicating motion thereto, of the halved cam, whereof one part is stationary and the other part oscillates to lengthen the action of the cam at alternate revolutions of the griper-carrying cylinder, substantially as set forth.

JNO. J. CLAUSE.
